UNITED STATES PATENT OFFICE.

JEREMIAH O'MEARA, OF NEW YORK, N. Y.

VALVE.

SPECIFICATION forming part of Letters Patent No. 240,755, dated April 26, 1881.

Application filed February 16, 1881. (No model.)

To all whom it may concern:

Be it known that I, JEREMIAH O'MEARA, a citizen of the United States, residing at the city of New York, in the county and State of New York, have invented certain new and useful Improvements in Valves; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to certain improvements in valvular devices, such as globe-valves, cocks, faucets, and check, pump, gate, and other valves for use in controlling steam, water, or gas.

The invention consists, first, in improvements in the seats for valves, whereby wearing away of the metallic seat is prevented by the jamming of an imperfect or worn disk-holder, and space left for sediment, &c., without interfering with the disk; and, second, in improved means for attaching the valve or disk holder to the stem or spindle.

In the accompanying drawings, illustrating my invention, in the several figures of which like parts are correspondingly designated, Figure 1 is a central vertical section of a globe-valve embodying all of my aforesaid improvements. Fig. 2 is a side elevation of the divided box and locking device separated, and of the spindle and valve-holder. Fig. 3 is a top view of a globe-valve shell, showing the valve-seat provided with two or more lugs to prevent the wear of said seat by jamming down the valve and to obtain sediment-space. Fig. 4 is a perspective view of the disk-holder and a portion of the spindle, illustrating the mode of attaching or swiveling said holder to the spindle to permit of its free movement and to prevent its accidental detachment in the operation of the valve; and Fig. 5 shows two modifications of this construction.

The divided automatic stuffing or packing removing box *a* is screwed to the bonnet *b*, as usual in my inventions, (shown in my Patent No. 213,239, dated March 11, 1879, and in my application No. 17,588,) and may be locked

thereupon by an inside nut, *c*, or an outside nut, *d*, engaging with threads on the bonnet. The outside nut being more accessible, no necessity existing for disconnecting the box, as in the case of the inside nut, to operate it, I consider said outside nut to this extent the more preferable.

Where the valve or disk holder containing composition disks is ground to obtain a new surface or tight fit, the less metal to be removed the more expeditious and economical the repairs. To this end I provide the seat, here designated *e*, (shown solid in my former application aforesaid,) with a cavity, *f*—that is to say, I make said seat partly tubular, so as to leave simply a narrow rim, instead of the whole body of the seat, to be removed in refacing or grinding.

The disk is herein designated *g*, and its holder *h* may be provided with the beveled, roughened, or equivalent disk-chamber, and said disk may be inserted as described in my hereinbefore-referred-to application.

The valve-seat may be a beaded or raised rim, *i*; and to prevent metallic contact of the holder *h*, as its disk wears away, with the web on which said seat is made, and also obtain a space for the collection of sediment and grit without interfering with the valve, I provide a plurality of lugs, *j*, adjacent to said rim *i*, to receive the holder as its disk is worn.

When the disk-holders are swiveled to the valve stem or spindle, as heretofore, they are liable to accidental detachment from said stem or spindle by the operating of the valve. My invention is designed to, and does, effectually prevent this; and it consists in flanged lugs *k* rising from the disk or valve holder, which receive the shouldered or flanged end *l* of the spindle *m* to prevent longitudinal displacement, the two being connected and held from lateral displacement by a pin, *n*, fitting in aligned sockets *o* *p* in the spindle and holder, respectively, this pin being secured from dropping out or displacement by a pin, or, better, a wire, *r*, passed through a transverse hole, *s*, in the stem, intersecting the pin-socket *o* therein. This wire is then secured by bending it around the stem. The pin *n*, of course, cannot pass the wire *s*, and hence it is held down in the

sockets, and while allowing perfect freedom of motion, even swiveling, to the holder, this construction absolutely prevents the accidental displacement or detaching of the holder. When the holder is to be removed the wires is taken out, the valve inverted, and the pin dropping down into the socket *o*, which is of greater length than the pin, and hence wholly contains it, then the holder is free to be slipped off the spindle. The spindle and holder are connected by placing the pin wholly within the stem-socket *o*, running the flanged end of said stem into the flanged lugs of the holder until the pin drops into the holder-socket *p*, when the pin may be secured by the wire *s* or the plug *t*.

The valve-holder is more readily ground or refaced if it be connected to the spindle by a square or other than round pin and sockets or cavities, such construction preventing the turning of the holder on its stem, but allowing it perfect freedom of motion otherwise. (See the lower part of Fig. 5, where this is indicated.)

In Fig. 5 I have shown the pin *n* in a socket the length of the spindle, and secured therein by a plug, *t*. This pin may be either round or square, or other shape than round, for the purpose next above described.

What I claim is—

1. A valve-seat having a plurality of adjacent lugs, *j*, to receive the valve-holder as it wears, to prevent metallic contact of the valve and its seat, and provide a sediment-space, substantially as described.

2. A valve-holder having flanged lugs *k* and a stem provided with the shouldered end *l*, to engage said lugs to hold the holder against accidental longitudinal displacement, combined with a removable pin, *n*, fitted in said valve-holder and spindle, and securely retained therein to prevent lateral displacement, substantially as described.

3. The socketed and flanged valve stem or spindle and the socketed and flanged valve-holder, combined with a pin placed in the sockets in both and removably retained therein by a suitable locking device, substantially as and for the purpose described.

In testimony whereof I affix my signature in presence of two witnesses.

JEREMIAH O'MEARA.
